UNITED STATES PATENT OFFICE.

ASAHEL D. SPERRY, OF ROCK ISLAND, ILLINOIS.

DETACHABLE STOVE BOARD.

Application filed April 25, 1924. Serial No. 708,897.

To all whom it may concern:

Be it known that I, ASAHEL D. SPERRY, a citizen of the United States, residing at 914 2nd Avenue, Rock Island, Illinois, have invented certain new and useful Improvements in Detachable Stove Boards, of which the following is a specification.

The invention relates to a detachable stove board.

10 It relates particularly to a stove board of the type used as a floor protector to prevent the heat of a stove from damaging the floor or the floor covering on which the stove rests.

15 In placing stoves in rooms having finely finished floors or having rugs or carpets covering the floor, it has been the usual practice to set the stove on top of a metal covered stove board which lays flat on the floor. These stove boards serve to prevent the heat that is thrown downwardly by the stove from damaging or igniting the floor, rug or carpet. The stove boards are usually 20 ornamented in some way to improve their appearance but even when so ornamented, they are not especially attractive.

25 Stoves are now being designed so as to present the appearance of a piece of furniture, generally a victrola. It is undesirable to place an artistic stove of this type upon a large stove board placed on the floor. At the same time, it is necessary to have some kind of a shield to protect the floor. The present invention has been devised for the 30 purpose of providing a floor protector or stove board which will be out of sight and will not detract from the artistic appearance of the stove with which it is used.

35 The general object of the invention is to provide an improved stove board.

40 A further object is to provide a detachable stove board which may be readily used with any type of stove and, when so used, is out of sight.

45 Another object is to provide a stove board which is detachably supported by the base of a stove.

50 Other objects and advantages of the invention will appear from the specification and drawings.

55 An embodiment of the invention is shown in the drawings in which—

Figure 1 is a perspective view of a stove with the detachable stove board illustrated in its working position.

Figure 2 is a plan view of the base of a stove with the stove board attached to it.

Figure 3 is a section of a stove base with the stove board attached.

The stove board is illustrated with a stove having an ornamental casing 1 supported by a rectangular base 2. A heating unit is located inside the casing, the unit being smaller than the casing. Fuel is fed into the heating unit through the door 3 and circulation of air takes place through openings in the bottom of the stove and openings 4 at the lower sides of the casing, the air passing between the casing and the heating unit and out through the openings 5 in the top 70 of the casing. The casing is artistically designed and preferably enamelled so as to resemble a wood finish with the object of making the stove have the general appearance of a piece of furniture.

75 While the stove board has been illustrated with an ornamental type of stove, and while it is particularly useful with this type, it is to be understood that it may be used with other suitable types of stoves.

80 The stove board has a body portion 10 forming a heat resisting shield. This body portion may be made of any suitable material such as asbestos, sheet metal with an asbestos covering, or simply of metal. The size of the body portion can be varied to suit the requirements. In the stove illustrated, the body portion is made approximately square and smaller than the base of the stove to leave a space between the edges 90 of the stove board and the stove base to provide an air passage so that there will not be any interference with circulation of air through the bottom of the stove. Its size is sufficient to protect the floor or floor covering because the heating unit is smaller than the base. In stoves where air is not taken in at the bottom, the body portion of the stove board may be made larger and almost the same size as the stove base. In stoves 100 which have circular bases, the body portion of the stove board may be made circular.

105 Pivoted on opposite sides of the body portion are bails 11 and 12. These are preferably made of spring wire, bent to U-shaped form, the arms of the U being bent outwardly and extending through openings in the bearings 13 on the body portion 10. These bearings are formed by cotter pins which are fixed in openings in the body portion.

2
with the eyes of the cotters on the under side of the body. The bent ends 14 of the bails extend through the cotted eyes and the resiliency of the wire holds the ends in place.

Most stoves have separate bases of either a rectangular or circular shape supported at some distance from the floor by stove legs. In the stove illustrated, the base is substantially rectangular and comprises side members 15 supported by legs 16. The side members are flanged at 17 to receive the casing 1 of the stove and they are also provided with one or more recesses 18. These recesses 15 are normally present in the side members as a result of the usual cross section that is adopted for side member construction.

The recesses in the sides of the stove base are utilized in attaching the stove board. The bails 11 and 12 are of such proportion that when they are extended outwardly in planes parallel to the plane of the body portion of the stove board, the combined width of the stove board and bails is slightly greater than the distance between the inside surfaces of two of the opposite sides of the stove base. The stove board is attached by placing it under the stove base and raising it to the dotted line position illustrated in Figure 3. In this position, the bails 11 and 12 can be swung downward so that the combined or total width of the stove board plus the bails can be varied by varying the position of the bails. The person placing the stove board in position grasps the bails 11 and 12 and raises the stove board to the dotted line position and places the bails in the recesses 18 in the side of the base. He then pulls down on the stove board and moves the body past center to the full line position illustrated in Figure 3. A toggle action is thus secured and the body of the board moves downwardly until the bails contact the body at the points 19. The stove board is then in position and it is firmly held there. It may be easily removed by pushing it upward to the dotted line position and allowing the bails 11 and 12 to drop downwardly after which it can be moved down and out from underneath the stove.

It is important to note that the stove board can be attached or detached after the stove is assembled and without moving or lifting the stove. This is a marked improvement over the old type in which the heavy stove had to be moved whenever the stove board was placed in or taken out of its position.

The resilient construction of the bails improves their action because it allows them to yield a certain amount and the spring of the parts also tends to hold the board more firmly in position.

When the board is to be used with bases

of different size, bails of different size or shape can be employed or their mounting can be changed by providing differently located holes in the body portion of the stove board for the cotted pins forming the bearings for the bails. Since the various dimensions of stoves on the market can be readily determined, a variety of sizes of bails and a variety of shapes of stove board can be readily provided to meet the requirements.

A stove board of this type may be employed with most of the stove bases ordinarily in use without altering their construction. On the other hand, when it is known that a stove board of this type is to be employed with a stove, the stove base or the stove may be constructed to receive the board. For example, lugs 20 may be cast in the base in spaced relation so as to center the bails 11 and 12 on the base. It will be readily appreciated that these lugs are not absolutely necessary because the stove board can usually be centered near enough without their use but they are an improvement that automatically centers the board. Inwardly extending lugs 21 can also be cast on the base to provide a better bearing surface for the bails 11 and 12 so that, in case there is some discrepancy in the manufacture of the board or the stove such that the bails do not seat well, they will nevertheless not drop away from the sides of the stove base because they will be supported by the lugs 21.

When this stove board is in position, as illustrated in Figure 1, it is entirely out of sight and it does not detract from the appearance of the stove. Air has a chance to circulate both above and below it to form a heat insulating space both above and below to prevent any downwardly radiated heat from injuring the floor or the floor covering. The construction is simple; it is much less expensive than the ordinary stove board; and it may be inserted or removed without having to move the stove.

The method of attaching the stove board that has been described and illustrated is the preferable method but other means of attaching it could be employed if desired.

It is to be understood that the construction shown is for purposes of illustration only and that variations may be made in it without departing from the spirit and scope of the invention as defined by the claims.

I claim:

1. The combination with a stove of the type adapted to rest on the floor of a building and to be used for heating or for cooking purposes, said stove having a heating unit supported in spaced relation to the floor by spaced downwardly extending legs which rest on the floor independently of a heat resisting shield, of a detachable heat resisting shield of such size that it may be

- positioned under the heating unit through the opening between the stove legs while the stove remains in position, and means associated with said shield for supporting it between the heating unit and the floor and in spaced relation to both, said means being constructed so that, when positioned for supporting the shield, it is not visible from any point from which the stove is normally observed.
2. The combination with a stove having a base supporting a heating unit in spaced relation to the floor, said base having spaced downwardly projecting legs adapted to rest on the floor, of a detachable stove board of size sufficient to protect substantially the entire area under the heating unit but of a size to permit it to be placed under the stove through the openings between the legs, said stove board carrying connecting devices by means of which it may be quickly and easily attached to and detached from the stove after it has been placed under the heating unit through the openings between the legs of the base and without changing the position of any part of the stove, said connecting means serving to support the stove board between the heating unit and the floor in spaced relation to both and in a position where it is normally invisible.
3. The combination with a stove having a heating unit and a base for supporting the heating unit in spaced relation to the floor, of a detachable stove board supported by the base between the heating unit and the floor and in spaced relation to both, and means including toggle connections for connecting the stove board to the base so that it may be quickly and easily attached to and detached from said base while the stove remains in position.
4. The combination with a stove having a heating unit and a base for supporting the heating unit in spaced relation to the floor, said base having spaced, downwardly projecting legs adapted to rest on the floor, of a heat resisting shield of size sufficient to cover substantially the entire area under the heating unit, said shield also being of such size that it may be placed under and removed from under said stove through the openings between the legs of the base, and toggle connections carried by said shield adapted to contact the sides of the base so that the shield can be quickly attached to the stove by placing it under the heating unit through the openings between the legs, raising it to a position to permit the toggle means to contact the sides of the base, and pulling the toggle past center, whereby the shield is supported by the base between the heating unit and the floor and in spaced relation to both, said shield being removable by pushing it upward to cause the toggle connections to pass over center, thereby disconnecting the shield from the base and permitting it to be removed through the openings between the legs.
5. A detachable stove board or floor shield for stoves of the type having a heating unit supported above the floor of a building on spaced legs and adapted to be used for heating or cooking purposes, having a heat resisting body portion adapted to be placed under the heating unit of a stove through the openings between the supporting legs while the stove remains in position, and means carried by said body portion for supporting it between the heating unit of a stove and the floor and in spaced relation to both, said means being constructed so as to be hidden by the stove when placed in position to support the stove board to thereby make the stove board and supporting means invisible from all normal points of observation of the stove.
6. A detachable stove board for stoves of the type having a heating unit supported in spaced relation to a floor by a base having spaced legs, comprising a heat resisting body portion of size sufficient to cover substantially the entire area under the heating unit, and means carried by the stove board for quickly and easily attaching it to and detaching it from a stove without changing the position of any part of the stove, said means serving to support the body portion of the stove board between the heating unit of a stove and the surface upon which the stove rests and in spaced relation to both and in a position such that it is normally invisible.
7. A stove board or floor shield having a heat resisting body portion and two bails adapted to contact the interior sides of the base of a stove, one of said bails being pivoted on the under side of the body portion toward one side thereof, and the other being pivoted to the under side of the body portion toward the opposite side thereof, whereby said bails form toggle connections by means of which the stove board may be quickly attached to and detached from a stove and held in position on the stove through the contact of the bails with the interior sides of the base of the stove.
8. A stove board having a heat resisting body portion, and two bails, one pivoted on the under side of the body portion toward one side and the other pivoted to the under side of the body portion toward the opposite side whereby the board may be detachably connected to the base of a stove.

In testimony whereof, I affix by signature.
ASAHEL D. SPERRY.
